UNITED STATES PATENT OFFICE.

JAMES L. FRAZIER, OF PEORIA, ILLINOIS.

DESIGN FOR A ROPE-COUPING.

SPECIFICATION forming part of Design No. 34,940, dated August 18, 1901.

Application filed June 10, 1901. Serial No. 64,045. Term of patent 14 years.

To all whom it may concern:

Be it known that I, JAMES L. FRAZIER, a citizen of the United States, residing at Peoria, in the county of Peoria and State of Illinois, have invented and produced a new and original Design for a Rope-Coupling; and I do hereby declare that the following is a full, clear, and exact description of the invention, which will enable others skilled in the art to which it appertains to make and use the same.

This invention relates to a new and original design for a rope-coupling, which may be understood from the following specification, with the aid of the accompanying drawings, in which—

Figure 1 is a perspective view of the complete coupling. Fig. 2 is a plan view of the same.

The coupling consists of a main body portion, substantially square in cross-section. At the top of this body is a round stem which gradually tapers toward its top and terminates in a square end. At one side of said square body is a projecting button, and in

the bottom is a dovetailed groove, the outline of which is shown in Fig. 1.

The top portion of the coupling consists of a curved shell open at both ends, one end being internally threaded.

The third member of the coupling consists of a body having two depending ears, which form an inverted U, and in the extremity of each ear is a bolt-hole. At the top is a dovetailed tongue of the same shape as the groove in the main body portion. The square body of the main body portion is largest at the bottom and it tapers toward the top, as shown.

Having thus described my invention, I claim—

The design for a rope-coupling as herein described and shown.

In testimony whereof I affix my signature in presence of two witnesses.

JAMES L. FRAZIER.
